UNITED STATES PATENT OFFICE.

HERMAN G. PAPE, OF NEWARK, NEW JERSEY.

ACOUSTIC DIAPHRAGM.

Application filed January 14, 1925. Serial No. 2,358.

This invention relates to magnetic acoustic diaphragms, such as are used in telephone receivers, radio head phones and kindred speech reproducing appliances.

An ideally correct diaphragm would be one with maximum flexibility and resiliency, that is, which would offer no resistance to deflection but which would return instantly to its normally position on the release of the magnet pull thereon, and which further contains magnetic material in sufficient quantity and so arranged as to shunt all of the magnetic lines of force without loss in the most direct path through the diaphragm between the magnet poles.

In the use of most thin iron diaphragms much of the magnetic force in the magnetic field, however, is lost or is ineffective to vibrate the diaphragm. In other words, the maximum energy of the magnet is not utilized for the reason that all of the lines of force in the magnetic field are not bent, diverted or shunted through the diaphragm.

My invention contemplates the increased utilization of the magnetic force acting on the diaphragm and induced by the magnets customarily used in electrical sound reproducing devices without interfering materially with the original flexibility and resiliency of the diaphragm and contemplates further the provision of a diaphragm wherein the tendency of the diaphragm to vibrate at its natural period and the consequent tendency to distort the sound to be reproduced is substantially eliminated. My invention contemplates further the provision of an economical, rapid and efficient method for the production of such diaphragms.

My improved diaphragm is so designed that it may be readily applied to various instruments employing magnet poles of greatly diversified proportions, shapes, strength, and arrangements, and is advantageous, when applied to magnet poles of any shape or type.

The various objects of my invention will be clear from the description which follows and from the drawings, in which,

Fig. 1 is a plan view of one type of the magnetic poles of the conventional magnetic spool head showing a portion of the diaphragm seat.

Figs. 2 and 3 are similar views of the magnets and the poles thereof, forming part of an electrical sound reproducer, illustrating how widely the proportions of the poles vary

in those reproducers of this type which are in ordinary use.

Fig. 4 is a similar view of the magnet structure wherein a central pole is used.

Figs. 5, 6 and 7 are similar views of similar types of magnets showing the diversified proportions customarily used in magnet poles of this type.

Fig. 8 is a plan view of one form of my invention as it appears applied to that arrangement of magnet poles shown in Fig. 7.

Figs. 9, 10, 11, and 13 are plan views of various forms of my improved magnetic piles which may be applied to a diaphragm.

Fig. 12 is a vertical section of a diaphragm showing one form of my improved loading.

Fig. 14 is a partial vertical section of a diaphragm to which another form of my invention has been applied.

I have found that the efficiency of a diaphragm of any practical shape is greatly enhanced by the disposition of the central portion thereof of material which is attracted by but which is not permanently magnetized by a magnet, (and which will hereinafter be called "magnetic material") provided that the material so added does not materially lessen the flexibility of the diaphragm. For the purpose of illustration only, I have shown my invention applied to directly actuated flat disc diaphragms though it is to be understood that my invention is applicable as well to flat, corrugated, circular, square, triangular, conical, tubular and other shapes of diaphragms. The magnetic material above mentioned may take various forms, such as a pile of finely divided particles, fine wire disposed in a suitable manner near the central portion of the diaphragm or a combination of wire and finely divided particles.

Due to the wide variation in the types and proportion in magnets H used in electrical reproducing devices, as illustrated in Figs. 1 to 7 inclusive, I have found it advisable to arrange the magnetic material magnetically reinforcing the diaphragm disc in polygonal or circular form at or near the central portion of the disc at which point the additional material is in the most direct path of the magnetic lines of force of all types of magnet poles, whereby the energy of the magnet instead of being largely dissipated, is utilized by the diaphragm, and the sound reproducing vibrations of the diaphragm are intensified.

It will be understood that in radio sound

reproducers wherein weak electrical currents are used, the amount of magnetic material added would be very small, and that where powerful electrical or magnetic impulses are employed the amount of said material would be large in proportion.

To provide a path for the lines of force which is applicable to the various forms of magnet poles A and B in common use, the

- 10 magnetic material should be deposited on the diaphragm D in the magnetic field induced by the magnets H, and as nearly as possible along paths which are common to the lines of force for any type or shape of magnet. It will
- 15 be understood, however, that if a diaphragm is to be used in a single definite unvarying position in connection with a magnet of predetermined force and proportions, the disposition and arrangement of the reinforcing
- 20 material would then depend upon the positions of the magnetic lines of force of greatest strength. The positions of said lines may be determined by dropping finely divided particles of magnetic material upon a dia-
- 25 phragm arranged on the magnet poles in its predetermined operative position. The particles arrange themselves along the lines of force, and if a sufficient number of said particles are deposited on the diaphragm, there
- 30 results what I will call a "pile" of magnetic material arranged to utilize most effectively the magnetic energy of the particular magnet for that particular position of the diaphragm.

I have found, however, that it is impractical to place a diaphragm on its seat S in contact with or near the magnet poles in exact predetermined position and to retain said diaphragm on its seat in unvarying position.

- 35 For this reason I prefer to arrange the magnetic material in circular or polygonal form as nearly as possible about the line C common to the various magnetic fields at the center of the diaphragm so that the magnetic lines of force of greatest strength, at all times and in
- 40 all positions of the diaphragm, pass through the magnetic reinforcing pile. The arrangement of the pile in the form described has the further advantage that the flexibility of the diaphragm is not materially altered since said
- 45 diaphragm is not mechanically but only magnetically reinforced, as will be pointed out hereinafter. I prefer to use iron or silicon steel for the magnetic material above referred to.

- 50 55 In view of the variations in size, shape and proportions of the magnets H and their poles A and B, I have designed a diaphragm wherein the arrangement of the magnetic reinforcement is substantially a compromise de-
- 60 signed to secure maximum practical efficiency in all positions of the diaphragm and for all types of magnets. I have found it desirable to gradually decrease the amount of magnetic material G as the outer peripheral edge of the pile is approached while providing points,

projections, or arborescent branches, in the pile radiating from the center thereof whereby the resistance to the magnetic flux is gradually increased as the periphery of the pile is approached. The points, extensions, 70 branches, or twig-like arborescent projections of little height aid further in increasing the magnetic pull on the diaphragm by the provision of a comparatively large area of more or less powerful magnetic reinforcement and 75 the utilization or bending of those stray lines of force which might otherwise fail to be drawn through the magnetic pile or the diaphragm.

In Fig. 9 I have illustrated the members W 80 of wire or other suitably shaped magnetic material arranged radially on the diaphragm and have further illustrated the magnetic pile G, the base of which is in the general form of a triangle. Near the ends of the wire W, I have shown a comparatively small amount of finely divided particles branching out therefrom. In this arrangement the lines of force in the magnetic pile are bent to follow approximately the path indicated by the circle 85 C while the flexibility and resilience of the diaphragm is not lessened to any appreciable degree, since the pile is itself flexible and substantially non-resistant to flexure.

In Fig. 10 the pile G reaches its greatest height around a circle spaced outwardly from the center thereof, said pile being arranged in the form of a polygon more or less star-shaped having arborescent branches near the ends thereof for the reason set forth above.

In Fig. 11 a pile of another shape is illustrated in which inwardly extending points or projections are used.

Fig. 8 illustrates a similar arrangement, except that the wire W is arranged in a circular 105 coil and the pile G is of the general form shown in Fig. 10.

In Fig. 13 I have illustrated a further modification of the form shown in Fig. 11, wherein a wire of magnetic material in the general 110 form of a pointed star is used in combination with a magnetic pile of finely divided particles.

Fig. 14 shows clearly the variations in the height of the magnetic pile G and shows said 115 pile combined with a ring W of magnetic material preferably circular in form, while Fig. 12 shows a series of rings W of gradually decreasing height combined with a pile G.

In carrying out my improved method for 120 the formation of the magnetic pile, and the attachment thereof to the diaphragm, I prefer to coat the diaphragm near the center thereof with suitable adhesive material which is non-brittle and soft when dry, such as gum 125 rubber, preferably dissolved and in liquid form, and then to drop from a point above said diaphragm a predetermined quantity of finely divided particles on to said diaphragm, whereby the particles adhere to the dia- 130

phragm in an area of predetermined shape and form a pile of substantially the form of a frustum of a hollow cone. The particles settle to the bottom of the gum rubber and on allowing the solvent of the rubber to evaporate a pile is formed varying in height and incorporated with the diaphragm in such a manner that said pile is extremely flexible. I have found gum rubber the best adhesive to use for this purpose by reason of the fact that the flexibility of the diaphragm remains substantially unaffected by the addition thereto of the pile in the manner described. However, if desired, said particles may be dropped on to the diaphragm before the adhesive material is applied thereto, provided that the diaphragm is first placed in position over the magnet poles, after which the cementing operation may be performed. This process may be varied by the combination of the two methods above described, that is, first forming a pile of predetermined shape and then adding thereto more magnetic material pulled into position by the magnets with which the diaphragm is to operate.

The wire W or the plate M may be combined with the finely divided particles at the same time or later, if desired. After the pile has been constructed, if a small quantity of adhesive material is then dropped thereon, said pile will be caused to cohere and to become secured to the diaphragm in such a manner as to allow the diaphragm to be flexed or to be vibrated by the magnets operating thereon without material resistance thereto, since the adhesive is itself flexible and the arrangement of the wire is such that no resistance is offered thereby to the vibration of the diaphragm.

It will be understood that in place of varnish, other cementing agents, such as, gum, rubber, celluloid or other lacquers, may be used as adhesives or preservatives.

I have found that by the deposition of the proper quantity of magnetic material in a pile of proper form and height depending on the magnet with which the diaphragm is to be used, the tendency of the diaphragm to vibrate at its natural frequency is practically eliminated whereby the sound reproduction is not distorted or interfered with.

I have found further that the volume of sound is greatly increased by reason, I believe, of the greater utilization of the magnetic energy of the magnets, and of the consequent greater amplitude of vibration of the diaphragm.

It will be seen that the shape of the pile may be predetermined so that my improved diaphragm having a magnet pile thereon may be used in connection with many types of magnet poles widely varying in proportions and arrangements.

It will further be seen that various changes may be made in the method of making the

magnetic reinforcement and in the shape and proportions thereof without departing from the spirit and scope of this invention as set forth in the appended claims.

I claim:

1. In a sound instrument, a diaphragm having plane surfaces free of loading material at the central and outer parts thereof, and magnetic comminuted loading material arranged in a comparatively narrow annular ring concentrically on one of said surfaces about the center of said diaphragm and in a pile for shunting the magnetic lines of force through said pile while substantially maintaining the resilience and flexibility of said diaphragm, said pile being superposed upon and secured to the said surface of said diaphragm and serving to increase the effective thickness thereof.

2. A diaphragm adapted to be used in sound instruments wherein the magnet poles have varied proportions, shapes and arrangements, comprising a flexible, resilient disc, plane unmarred faces on said disc and a pile of comminuted magnetic material arranged in an annular ring about the center of said disc, the height of said pile being a minimum at the outermost periphery thereof, and varying at points at different radial distances from the center of said diaphragm.

3. A diaphragm for sound instruments having magnetic poles varying in size, shape and arrangement, including a narrow annular pile of comminuted magnetic material forming an approximately circular shunt magnetic path between said poles about the center of said diaphragm.

4. In a diaphragm adapted for operation in sound receivers having magnetic poles varying in size, position and arrangement, an annular magnetic pile varying in height arranged concentrically about the said diaphragm for shunting the magnetic lines of force through said pile while substantially maintaining the flexibility of said diaphragm.

5. In a diaphragm, adapted for operation in sound receivers having magnetic poles varying in size, position and arrangement, an annular pile of finely divided particles of magnetic material arranged about the center of said diaphragm, the height of said pile being a minimum at the peripheral edges of said pile, and a maximum between said edges.

6. In a diaphragm, adapted for operation in sound receivers having magnetic poles varying greatly in size, position, and arrangement, finely divided particles of material arranged in an annular pile about the center of said diaphragm, and a magnetic member arranged on said diaphragm about the center thereof and incorporated with said pile for decreasing the resistance to the magnetic flux while substantially maintaining the original flexibility and resilience of said diaphragm.

7. A diaphragm for sound instruments having magnetic poles varying in size, shape and arrangement, including an annular pile varying in height of magnetic material, forming an approximately circular shunt magnetic path between said poles, and arranged about the center of said diaphragm and substantially radial extensions at the base of said pile.
8. A diaphragm including a pile varying in height of finely divided particles of magnetic material arranged substantially in the form of a ring about the center of said diaphragm.
9. A diaphragm having plane unmarred surfaces and including finely divided magnetic material arranged annularly and concentrically about the center of said diaphragm in a pile of varying height resting on and extending above one of said surfaces and flexible cementitious means for causing said material to adhere together and to one of said surfaces for varying the effective thickness of said diaphragm at said pile.
10. The method of making an acoustic diaphragm, comprising the provision of a disc, applying gum rubber dissolved in a solvent therefor to the center of said disc, dropping finely divided particles of magnetic material from a point above said disc into said gum rubber while the disc is in the field of a mag-
- net which produces a magnetic field similar to that of the magnet to be used with said diaphragm, allowing said particles to settle in the gum rubber until said particles come to rest and allowing the solvent for the gum rubber to evaporate.
11. A diaphragm for sound instruments having magnetic poles varying in size, shape and arrangement, including an annular loading pile of magnetic material forming an approximately circular shunt magnetic path between said poles, and arranged about the center of said diaphragm so that said center is free of magnetic material.
12. A diaphragm including a magnetic loading arranged substantially in the form of a ring superimposed upon the surface of and about the center of said diaphragm, and of varying height at different distances from the center.
13. A diaphragm having plane, unmarred surfaces and including a magnetic loading arranged annularly and concentrically about the center of said diaphragm and extending above one of the said surfaces and flexible cementitious means for securing said loading to the diaphragm.

In testimony whereof I have signed my name to this application.

HERMAN G. PAPE.
